DIFFERENTIAL-RECOIL GUN.

1,072,350.

Specification of Letters Patent. Patented Sept. 2, 1913.

Application filed December 8, 1911. Serial No. 664,594.

To all whom it may concern:

Be it known that I, EMIL MÜLLER, engineer, a subject of the German Emperor, residing at 27 Jordanstrasse, Dusseldorf, Germany, have invented certain new and useful Improvements in Differential-Recoil Guns; and I do hereby declare the following to be a full, clear, and exact description of the invention, such as will enable others skilled in the art to which it appertains to make and use the same.

The determination of the amount of braking action required during the recoil of differential recoil guns depends upon the speed which is due to the recoil energy produced by firing, less the energy produced by the return speed at the moment of firing. The smaller, therefore the forward velocity is at the moment of firing, the more powerful must be the braking effect during recoil. A larger braking pressure however requires that the cradle must be more strongly constructed, by which the advantage of the differential recoil gun as compared to the ordinary type, which consists in the lighter construction of the former for equal dynamic energy, is very largely lost. Also the higher pressure unfavorably affects the stability of the gun during the recoil.

The present invention relates to a differential recoil gun, in which the advantages peculiar to this system are fully made use of, by so constructing the parts of the brake, that there is no braking action during the running out of the barrel to the firing position, and a brake action in running out only occurs, if the barrel goes beyond the firing position in consequence of a misfire.

Several constructions according to the invention are shown in the accompanying drawings.

Figure 1 shows a construction in longitudinal section in the firing position; Fig. 2 shows the same construction at the end of the recoil. Fig. 3 is a section on the line 3—3 of Fig. 1, and Fig. 4 is a section on the line 4—4 of Fig. 2. Fig. 5 shows a somewhat different construction in the position, which the barrel attains, when in consequence of a misfire, it has passed the firing position. Figs. 6 and 7 show other modifications in the firing position.

In the construction according to Figs. 1—4, around the inner brake cylinder *a*, which is

connected in the usual manner with the barrel, there is a second cylinder *b* of such dimensions, that the cross section of the tubular space between them is as large as the acting surface of the piston *c*. The wall of the inner cylinder *a* is provided at the rear end with openings *e* for the flow of liquids, which must be at least as great as the acting surface of the piston. The piston is provided in the usual manner with liquid passages in the form of openings *d* which a movable disk *h* closes during the recoil in known manner. Also channels *f* are formed in the inner wall of the cylinder *a*, which form openings for the passage of the brake fluid during the recoil.

If the piston *c* is supposed to be solid, that is without the openings *d*, and the cylinder to be also without the channels *f*, then during the movement from the position represented in Fig. 2, in which the piston *c* moves relatively to the cylinder *a* in the direction shown by the arrow, the fluid would be displaced by the piston, so as to pass through the openings *e* in the cylinder, then to be further moved in the opposite direction between the two cylinders *a* and *b* and finally arrive at the other side of the piston through the openings *g* provided at the forward end of the cylinder *a*. But since in fact the channels *f* are provided for the brake action during the recoil, and also the piston *c* is provided with the apertures *d*, which during the run out (Fig. 1) are opened by the disk *h* being moved forward, the openings *e* and *g*, as well as the cross section of the cylindrical space *r*, can be made somewhat smaller than would be necessary according to the above assumptions, since on the run out, part of the braking fluid passes through the openings *d* and the channels *f* to the other side of the piston.

In order that during the recoil only the channels *f* shall be kept open and consequently that the right amount of braking should occur, a circular disk *i* is arranged on the piston rod, which during the run out is pressed back by a spring *i'* so as to uncover the openings *g*, but during the recoil is displaced by the brake pressure, so as to cover these openings.

The gun barrel is held in position at the end of the recoil in the manner known in connection with differential recoil guns, by

a locking device *l* (Fig. 2), whereby the return spring is held in compression. If the locking device is released, the return spring *k* drives the barrel forward, and when it has traversed the distance *s*, the trigger *m* of the breech block meets the fixed stop *n* of the cradle and the gun is fired. The barrel then recoils in consequence of the backward impulse, and at the end of the recoil it is again held by the locking device *l*, in order to be again charged and aimed.

If a misfire occurs when the firing position is reached, the barrel, since the shot has not been fired, continues its forward movement, which must then be braked. This is effected by a plug *o* at the rear end of the cylinder *a* entering an open-end chamber *o'* which is shown in the form of a boring in the piston rod. Since this chamber *o'* is filled with brake fluid and the plug *o* is provided with grooves, or gradually tapers with a suitably formed curve, the fluid in the chamber *o'* is pressed outward, as the plug *o* enters, and is forced past the annular cross section between the plug and the boring, which section decreases as the forward movement continues. In this way the braking of the gun barrel is effected, if it passes the firing position in consequence of a misfire. This position of the parts is shown in Fig. 5, which agrees essentially and in respect to the above described parts with the construction according to Figs. 1-4, but has in addition an equalizing device, which comes into action, when the gun misses fire or if the brake fluid is heated.

This device consists in a piston *p*, which is placed in an additional chamber in the cylinder *a* and is ordinarily held in the dotted position by means of a spring *q*. If a misfire occurs or the braking fluid expands by heat, the fluid passes through the openings *t* behind the piston *p*, which makes room for the brake fluid by compressing the spring *q*. If the brake cylinder is filled when the parts are in the position which they assume when a misfire occurs, that is, as shown in Fig. 5, and the barrel is then brought into the position for aiming as shown in Fig. 2, a vacuum is produced in the brake cylinder, due to the piston rod emerging from the brake cylinder. This vacuum would also be formed to a less extent, when the barrel during the run out is in the firing position, and would be destroyed, when the piston rod, in consequence of a misfire, again enters completely into the brake cylinder.

In the normal function of the gun, in which the recoil takes place from the firing position, there would be no braking action during the first part of the recoil stroke, but only when the piston has displaced the brake fluid, so that the inner cylinder space is again completely filled. To avoid this drawback, according to the present invention, the

brake cylinder is filled, when the parts are in the firing position shown in Fig. 1. In order that the cylinder should be filled in this position, the above mentioned equalizer *p* is arranged, which allows the brake fluid to enter the special compartment in case the gun misses fire. When the barrel again returns from the misfire position, the piston *p* again assumes the dotted position, under the pressure of the spring *q*.

The construction shown in Fig. 6 differs from those previously described, in that only one cylinder is provided. The piston *c* is provided as before with the apertures *d*, which, in common with the channels *f*, allow the passage of the brake fluid during the run out. In this case the vacuum produced by the protrusion of the piston rod from the cylinder acts, in conjunction with the correspondingly proportioned dimensions of the apertures *d*, which with the recesses *f*, allow for the passage of the fluid, so that there is no braking during the run out, except when, in the case of a misfire, the firing position is passed, as shown in Fig. 6, and the plug *o* enters the chamber *o'* in the piston rod. The fluid equalizer *p* then comes into action. The action of the vacuum alone during the run out—without taking into account the apertures for the flow of the fluid—would have the same effect, as if the fluid was displaced before the piston until the vacuum was destroyed, during which no braking action would take place. On taking the apertures into account, a passage of the fluid would occur during this part of the movement, so that during the rest of the run out movement, a smaller part need be brought to the other side of the piston. Consequently by suitably proportioning the apertures the braking can be avoided. Also the amount of the vacuum can be determined by suitably proportioning the dimensions of the piston rod. During the recoil the disk *h* lies over the openings *d* and the fluid can only pass through the recess channels *f* to the other side of the piston and these are so proportioned that the required braking takes place.

The construction shown in Fig. 7 agrees with that in Fig. 6, in that only one cylinder is provided. The piston is here differently constructed and has apertures *x*, which are closed during the recoil by a valve *y* connected to a disk *z*. During the run out the valve opens on account of the direction of flow of the fluid and allows the passage of the fluid to the other side of the piston without any braking action, which coöperates also in this case with the influence of the vacuum due to the protrusion of the piston rod. Also in this case the recess channels *f*, serve for the restricted passage of the fluid during the recoil. The plug *o* which effects the braking action in case of a misfire is in

this example attached to the piston, while the chamber of is formed in a cylinder inserted in the brake cylinder.

I claim as my invention:

- 5 1. A differential recoil gun having, in combination with a recoiling barrel, braking means comprising a fluid-containing cylinder having double walls forming an intermediate space, and also having openings 70 from said space into the cylinder at the ends thereof, a piston within said cylinder, said piston and cylinder having a relative movement, said openings allowing fluid to pass from one side to the other of the piston without creating any braking action during the run out of the barrel, and means for cutting off the free communication through said openings during the recoil of the barrel.
- 10 2. A differential recoil gun having, in combination with a recoiling barrel, braking means comprising a fluid-containing cylinder having double walls forming an intermediate space, and also having openings 75 from said space into the cylinder at the ends thereof, a piston within said cylinder, said piston and cylinder having a relative movement, said piston having openings therein for the passage of fluid during the run-out of the barrel, means for closing the 80 openings in the piston during the recoil, and means for closing the passage through the first mentioned openings during the recoil movement.
- 15 3. A differential recoil gun having, in combination with a recoiling barrel, braking means comprising a fluid-containing cylinder having double walls forming an intermediate space, and also having openings 85 from said space into the cylinder at the ends thereof, a piston within said cylinder, said piston and cylinder having a relative movement, said piston also having openings for the passage of fluid during the run-out 90 of the barrel, the openings into the cylinder 95 having at least the same cross-section as the effective end surface of the piston.
- 20 4. A differential recoil gun having, in combination with a recoiling barrel, braking means comprising a fluid-containing cylinder having double walls forming an intermediate space, and also having openings 100 from said space into the cylinder at the ends thereof, and a piston within said cylinder, said piston and cylinder having a relative movement, said piston also having openings for the passage of fluid during the run-out of the barrel, the openings into the cylinder 105 having at least the same cross-section as the effective end surface of the piston.
- 25 5. A differential recoil gun having, in combination with a recoiling barrel, braking means comprising a fluid-containing cylinder having double walls forming an intermediate space, and also having openings 110 from said space into the cylinder at the ends thereof, a piston within said cylinder between which and the latter there is a relative movement, fluid being designed to pass from one end of the cylinder to the other through said tubular space, the cross-section of such tubular space being at least as great as the effective end surface of the piston.
- 30 6. A differential recoil gun having, in combination with a recoiling barrel, braking means comprising a fluid-containing cylinder having double walls forming an intermediate space, and also having openings 115 from said space into the cylinder at the ends thereof, a piston within said cylinder having a rod projecting beyond the end of said cylinder, said piston and cylinder having a relative movement, coöperating means for braking the run-out of the barrel beyond the firing position in 120 the event of a misfire, said cylinder also having a separate chamber in communication therewith, and yielding means within said separate chamber designed to be automatically actuated to allow the fluid to pass into 125 said separate chamber in case of a misfire or expansion of the fluid.
- 35 7. A differential recoil gun having, in combination with a recoiling barrel, braking mechanism comprising a fluid containing cylinder which is designed to be full of fluid when the barrel is in firing position, a piston within said cylinder having a rod projecting beyond the end of said cylinder, said piston and cylinder having a relative movement, coöperating means for braking the run-out of the barrel beyond the firing position in 130 the event of a misfire, said cylinder also having a separate chamber in communication therewith, and yielding means within said separate chamber designed to be automatically actuated to allow the fluid to pass into said separate chamber in case of a misfire or expansion of the fluid.
- 40 8. A differential recoil gun having, in combination with a recoiling barrel, braking mechanism comprising a fluid - containing cylinder having double walls forming an intermediate space, and also having openings 135 from said space into the cylinder at the ends thereof, said cylinder having channels in its inner wall, a piston within said cylinder, said piston and cylinder having a relative movement, said openings allowing fluid to pass from one side of the piston to the other without creating any braking action during the run-out of the barrel, and means for au-

tomatically cutting off the free communication through said openings during the recoil of the barrel.

5 9. A differential recoil gun having, in combination with a recoiling barrel, braking 70 means comprising a fluid-containing cylinder having double walls forming an intermediate space, and also having openings from said space into the cylinder at the ends thereof, said cylinder having channels in its inner wall, a piston within said cylinder, said piston and cylinder having a relative movement, said piston having openings therein for the passage of fluid during the run-out of the barrel, means for closing the 80 openings in the piston during the recoil, and means for closing the passage through the first mentioned openings during the recoil movement.

10 10. A differential recoil gun having, in combination with a recoiling barrel, braking 85 means comprising a fluid-containing cylinder having double walls forming an intermediate space, and also having openings from said space into the cylinder at the ends thereof, and a piston within said cylinder, said piston and cylinder having a relative movement, said piston also having openings for the passage of fluid during the run-out 90 of the barrel, the openings into the cylinder 95 having at least the same cross-section as the effective end surface of the piston.

15 11. A differential recoil gun having, in combination with a recoiling barrel, braking means comprising a fluid-containing cylinder having double walls forming an intermediate tubular space and openings at its ends into said cylinder, a piston within said cylinder between which and the latter there is a relative movement, fluid being designed 100 to pass from one end of the cylinder to the other through said tubular space, the cross-section of such tubular space being at least as great as the effective end surface of the piston.

20 12. A differential recoil gun having, in combination with a recoiling barrel, braking mechanism comprising a fluid containing cylinder which is designed to be full of fluid when the barrel is in firing position, a piston within said cylinder having a rod projecting beyond the end of said cylinder, said piston and cylinder having a relative movement, coöperating means for braking the run-out of the barrel beyond the firing position in 120 the event of a misfire, said cylinder also having a separate chamber in communication therewith, and yielding means within said separate chamber designed to be automatically actuated to allow the fluid to pass into 125 said separate chamber in case of a misfire or expansion of the fluid.

25 13. A differential recoil gun having, in combination with a recoiling barrel, braking mechanism comprising a fluid - containing cylinder having double walls forming an intermediate space, and also having openings 130 from said space into the cylinder at the ends thereof, said cylinder having channels in its inner wall, a piston within said cylinder, said piston and cylinder having a relative movement, said openings allowing fluid to pass from one side of the piston to the other without creating any braking action during the run-out of the barrel, and means for au-

cylinder which is designed to be full of fluid when the barrel is in firing position, a piston within said cylinder having a rod projecting beyond the end of said cylinder, said 5 piston and cylinder having a relative movement, coöperating means for braking the run-out of the barrel beyond the firing position in the event of a misfire, said cylinder also having a separate chamber in communication therewith, and a spring held piston 10 within said separate chamber designed to be

automatically actuated to allow the fluid to pass into said separate chamber in case of a misfire or expansion of the fluid.

In testimony whereof, I have signed this 15 specification in the presence of two subscribing witnesses.
